UNITED STATES PATENT OFFICE

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY

METHOD OF AND MACHINE FOR OPERATING UPON SOLES

Application filed July 1, 1927. Serial No. 202,895.

This invention relates to methods of and machines for operating upon soles and to templets for use in such machines. The invention is herein illustrated with especial reference to reducing or thin edging the shanks of outsoles for McKay sewed shoes, although its usefulness in certain respects is not necessarily limited to performing this particular operation.

10 In the manufacture of outsoles for McKay sewed shoes it is often desirable for reasons well known in the art to make the reducing cuts at the flesh side of the sole. If the soles are reduced at the flesh side, and particularly 15 if the soles are subsequently to be molded, it is important to predetermine the locations of the forward ends of the reducing cuts with accuracy and uniformity at or in the immediate vicinity of the ball line in order to insure that, in the finished shoe, the sole margin will lie close to the upper at the break between the shank and the forepart of the sole. It is also important accurately and uniformly to locate the rearward ends of the 20 reducing cuts at the line where the breast of the heel is to be located in order to insure proper seating of the heel. It is furthermore desirable to have corresponding parts 25 of the reduced areas along the opposite lateral margins of the shank of the sole of the same width in order to secure the desired transverse contour at the outer surface of the shank. Soles which are to be shank reduced at the flesh side, however, are customarily channeled before the shank reducing 30 operation is performed and the soles are often distorted during the channelling to such an extent as materially to alter the swing of the sole and this distortion is liable to interfere seriously with the attainment of the desiderata above set forth.

One object of the present invention is to insure that the ends of the reduced areas shall be located with uniformity in the same 45 relative positions in different soles and that corresponding parts of the reduced areas shall be of uniform widths along the opposite lateral edges of the shank portions of the soles irrespective of any variations in the swing of the soles such, for example, as may

be caused by distortion of the soles during channelling operations.

With this object in view the invention, in one of its aspects, resides in the improved method of operating upon soles which consists in positioning a sole upon a sole-supporting templet, separately securing both ends of the sole against edgewise displacement upon the templet, operating upon the sole progressively lengthwise of the sole edge while utilizing the templet in gaging the relative movement of the sole and the operating means in the plane of the sole at one portion of an area to be operated upon, and gaging said relative movement from the sole itself along another portion of the area to be operated upon. As herein illustrated, a shank reducing or thin edging operation is performed by means of a rotary cutter; the sole is supported upon the templet and its toe and heel portions are secured against edgewise displacement relatively thereto; and the templet is adapted to co-operate with an edge gage to determine the locations of the ends of the reducing cuts at the ball and heel breast lines while the edge gage co-operates with the edge of the sole itself during the remainder of the cutting action to gage the widths of the reducing cuts.

When a sole has been distorted in the channelling operation so that the swing of the sole has been changed more or less as above described it will be evident that if the sole is secured at its toe and heel portions against edgewise displacement relatively to a templet 35 the relation of the shank portion of the sole transversely with respect to the templet will be different from that of a sole which has not been distorted but which has only a normal amount of swing, and further, that if the templet is relied upon to guide the sole relatively to the cutter while the shank reducing cuts are being made along the shank of the sole, the cuts at one side of the shank may be of different widths from corresponding portions of the cuts at the opposite side of the shank, the difference in width depending upon the amount which the sole is offset at the shank from its normal transverse relation to the templet.

To insure uniformity in the widths of corresponding parts of the reduced areas along the opposite lateral margins of the shank portion of the sole, and also to provide for locating the ends of the reduced portions at the desired predetermined points, the invention in one of its machine aspects consists in the provision of means for operating upon the margins of soles, comprising an operating tool, a sole supporting templet, and a gage, the operating tool and the templet being adapted for relative movement to transfer the point of operation of the tool along the margin of the sole, and the templet having a portion wider than the sole to control the operation of the tool at one part of the sole margin and another portion narrower than the sole to enable the sole itself, in co-operation with the gage, to control the operation of the tool at another part of the sole margin.

As herein illustrated, a rotary cutting tool is arranged to co-operate with a sole supporting templet which is adapted to be manipulated to cause the margin of the sole to travel progressively past the cutter, and a table, inclined relatively to the axis of the cutter, is arranged to support the templet so that the cut will be made at an angle to the surface of the sole. The illustrated gage consists of a roller mounted upon the table and arranged to project above the templet into the plane of the sole, and the templet is made larger than the sole at the forepart and heel portion to hold these portions of the sole away from the cutter. At its shank portion, however, the templet is narrower than the shank portion of the sole to enable the gage roller to leave the templet and engage only the edge of the sole, thereby gaging the cutting operation along the shank from the sole itself instead of from the templet. Between the forepart and shank portion of the templet and between the heel part and shank portion of the templet the opposite margins of the templet are shaped to co-operate with the gage roller to cause the cutter to begin and end its cutting operations at the desired points at the ends of the shank portion of the sole.

Invention is also to be recognized in the provision, for use in a shank reducing machine, of a sole supporting templet having means for holding a sole in fixed relation thereto, the templet projecting beyond the toe and heel portions of the sole to hold corresponding portions of the sole away from an operating instrumentality of the machine and having a shank portion which is narrower than the shank portion of the sole and which is arranged relatively to the latter to permit a reducing operation to be gaged from the edge of the sole itself.

The invention will be explained with reference to the accompanying drawings, in which

Fig. 1 is a view in side elevation of a ma-

chine embodying the invention in certain of its aspects and showing also the templet with a sole positioned thereon, the templet and sole being in section in the vertical plane of the axis of the cutter;

Fig. 2 is a front elevational view of the machine;

Fig. 3 is a plan view of the templet and the work showing the templet resting upon the work table and being guided by the edge gage roll and showing the work being operated upon by the cutter;

Fig. 4 is an edge view of the templet and the work; and

Fig. 5 is a cross-sectional view taken along the line V—V of Fig. 4.

In Figs. 1 and 2 of the drawings there is shown the head 8 of a rotary feather edging or shank reducing machine, such as that disclosed in United States Letters Patent No. 1,003,981, granted Sept. 26, 1911, on application of J. N. Busell. As shown, the head 8 is formed with spaced bearings 10 for a horizontal shaft 12 which carries at its forward end a cutter head 14. The shaft 12 is adapted to be driven from any suitable source of power by means of a belt 16 passing over a pulley 18 fast on the shaft between the bearings 10. The construction of the parts thus far described is substantially the same as that of corresponding parts shown in the Letters Patent above referred to.

The illustrated cutter head 14 is of the so-called barrel type, being of substantially cylindrical form and being provided with a plurality of cutter blades 20 having cutting edges projecting beyond the periphery of the cutter head.

To position the work at such an angle relatively to the axis of the cutter head that the blades 20 will bevel the margin of the work there is provided an inclined table 22, and to guide the work while it is being moved manually past the rotary cutter so that the shank reducing cuts will be located as desired there is provided a templet or pattern 24 which is adapted to support and carry the work and to co-operate with an idle edge gage roller 26 on the table.

The table 22 is mounted so that its inclination may be adjusted to vary the angle of bevel of the reducing cut. To this end, the rear portion of the table is pivoted at 28 to a block 30 carried by a bracket 32 which is secured to the front portion of the head 8 below the cutter shaft and the front portion of the table is connected by means of an extensible link 34 with a collar 36 carried by a hand screw 38, the shank of which is threaded through the lower portion of the bracket 32. The link 34 is pivoted at 40 and 42 to the table 22 and the collar 36, respectively, and the link may be lengthened or shortened to change the inclination of the table 22 by

manipulation of a right and left threaded turn buckle 44 which constitutes the middle portion of the link.

Provision is also made whereby any change in the angular or tilting adjustment of the work table 22 may be compensated for by appropriate vertical and horizontal adjustment of the table and whereby the table may be adjusted to accommodate soles of different thicknesses and widths. To effect the vertical adjustment of the table its pivotal supports 28 and 40 are adapted to be moved in unison by adjustment of the hand screw 38 and for this purpose the collar 36 and the block 30 are connected with the hand screw for up-and-down movement in unison therewith, the collar 36 being confined between the head of the hand screw and a collar 46 pinned to the shank of the screw 38, while the block 30 is confined between a collar 48 and a nut 50 each of which is secured to the hand screw. To lock the table in its vertically adjusted position a binding screw 52 extends through a vertically elongated slot 54 in the bracket 32 and is threaded into the block 30, the binding screw 52 being provided with a suitable check nut 56.

To enable the table 22 to be adjusted horizontally, the bracket 32 is threaded upon the forward extremity of a horizontal adjusting screw 60 which extends through the head 8 and is held against lengthwise displacement by means of an arm 62 rigid with the head 8 and arranged to straddle the screw 60 between the head 64 of the screw and a collar 66 pinned to the shank portion of the screw. The bracket 32 is held against turning about the adjusting screw 60 by means of a stud 68 which extends from the rear of the bracket 32 into a socket in a portion of the head 8. To lock the table in its horizontally adjusted position a binding screw 70 is provided, the end of which is arranged to engage the shank of the adjusting screw 60.

The templet 24 consists of a flat plate which is adapted to support a sole while the sole is being operated upon, the outline of the templet corresponding in a general way to the outline of the sole except that the portions of the templet which support the forepart and heel portions of the sole are wider than the corresponding portions of the sole for the purpose of holding these portions of the sole away from the reducing knife while that part of the templet which supports the shank portion of the sole is narrower than the corresponding portion of the sole to insure that the edge of the sole rather than the edge of the templet will engage the gage roller 26 to guide the work during operations upon the shank of the sole. To position the sole upon the templet and positively to hold the sole against edgewise displacement relatively to the templet while the sole

is being operated upon, the toe and heel ends of the templet are thickened, as indicated at 72, and are provided with curved shoulders 74 shaped to conform to the outline of the toe and heel ends of the sole, the arrangement being such that the ends of the sole will be held transversely centered with respect to the corresponding ends of the templet. As best shown in Fig. 3, the edges of the templet forward of the ball line B and rearward of the heel breast line H are spaced outwardly a considerable distance from the edge of the sole S, while in the vicinity of the ball and heel breast lines the edges of the templet slope inwardly toward the sole edge to enable the sole edge to be engaged by the cutter at these points. The inwardly sloping edges of the templet in the vicinity of the ball line are indicated at 75 in Fig. 3 while the inwardly sloping edges of the templet in the vicinity of the heel breast line are indicated at 76.

As hereinbefore mentioned the sole may be distorted in the channeling operation which precedes the shank reducing operation in such a way as to alter the swing of the sole. It will be evident that a sole thus distorted if placed upon the templet with its toe and heel ends transversely centered with respect to the templet the shank portion of the sole will be displaced from its normal transverse relation to the rest of the templet. This displacement of the shank portion of the sole may vary more or less in different soles of the same size, with the result that shank portions of different soles will not be uniformly positioned in the same transverse relation to the templet. If, therefore, the shank reducing cuts are gaged from the edge of the templet they might not be of uniform widths in different soles or at opposite sides of the same sole on account of the above-mentioned transverse displacement of the shank portion of the sole. To avoid this undesirable result and to insure uniformity in the width of the shank reducing cuts in different soles and at opposite sides of each sole, the portion of the templet which underlies the shank of the sole has been made narrower than the corresponding portion of the sole, as shown clearly in Fig. 3, the arrangement being such that both edges of the templet are spaced inwardly from the corresponding edges of the shank portion of any sole which may be used in connection with the templet. This construction insures that throughout the length of the shank portion of the sole the shank reducing cuts will be gaged from the edges of the sole itself instead of from the edges of the templet.

The gage roller 26 is mounted upon the rear portion of the table 22 and projects upwardly somewhat beyond the upper surface of the templet so that it will be engaged by the edge of the sole at the shank where the

templet is narrower than the sole. As shown in Fig. 3, the gage roller 26 is offset somewhat from the point of cutting in the direction of travel of the work so that the roller which projects above the templet and into the plane of the work will not interfere with the operation of the cutter.

In case there may be some tendency for the sole to curl upwardly at its edge provision is made for flattening out the edge of the sole and insuring that it will be held in contact with the templet while it is being operated upon. This result is accomplished by means of a presser foot 78 (Fig. 2) having a curved work-engaging portion located just in advance of the line of contact of the cutter with the work and arranged to travel along the margin of the sole as the sole is fed past the cutter. The presser foot 78 is provided with a vertical shank portion 80 slidably mounted in bearings formed on a bracket 82 carried by a guard 84 which encircles the cutter and is suitably mounted upon the head of the machine. The presser foot 78 is urged downwardly by means of a spring 86 secured at one end to a portion of the bracket 82 and at its other end to a collar 88 fixed to the shank of the presser foot. The collar 88 by engagement with the upper portion of the bracket 82 functions to limit the approach of the presser foot and the movement of the presser foot toward the table 22. As shown, a forked projection 90 on the collar 88 slidably engages a vertical stationary guide rod 92 to hold the presser foot from turning in its bearings in the bracket 82. If desired, and as herein shown, a second presser foot 94 may also be employed to hold the sole against the templet and the templet against the table, the second presser foot 94 being arranged to gage the sole at a point substantially opposite that being acted upon by the cutter. The presser foot 94 is shown as being mounted in a bearing 96 formed at the front of the guard 84 and it is urged downwardly by means of a suitable spring (not shown) which may be confined within the bearing 96 and the tension of which may be varied by means of an adjusting screw 98. The cutter guard 84 may be adjusted axially of the cutter to vary the transverse relation of the presser foot to the work. As shown, the cutter guard 84 is secured to a horizontal shaft 100 slidably mounted in a bearing 102 formed at the upper portion of the head 8 by means of an adjusting screw 104. The shaft 100 together with the cutter guard 84 and the presser foot carried thereby may be adjusted. A binding screw 106 is provided for securing the shaft 100 in adjusted position.

In using the apparatus herein described for shank reducing an outsole for a McKay sewed shoe the sole, after being grooved and channelled in the usual manner upon the grain side,

is placed channel side down upon the templet with the toe and heel ends of the sole engaged and located by the curved shoulder 74 of the templet and the sole thus held against edgewise displacement relatively to the templet. The templet is placed on the inclined table 22 and positioned with the edge of the pattern at the heel end against the gage roller 26. While holding the edge of the templet continuously against the roller 26, the operator manually feeds the templet in the direction of the arrow in Fig. 3 until the entire margin of the templet, except the portion at the extreme heel end thereof, has been moved past the gage roller. At the beginning of the operation the portion of the templet at the heel end of the sole holds the sole away from the cutter so that the latter is permitted to act upon the sole. When one of the portions 75 of the templet reaches the roller, however, the sole is moved into the path of the cutter at such a point that the cutter begins its shank reducing action at a predetermined point, preferably at the heel breast line. The sole is brought into contact with the cutter by movement of the sole toward the cutter in the plane of the sole or, in other words, by edgewise movement of the sole. Inasmuch as the templet is narrower than the sole at the shank, the edge of the sole is brought into engagement with the roller 26 very shortly after the cutter has begun its operation and thereafter, throughout the length of the shank portion of the sole, the sole is guided relatively to the cutter by engagement of the roller 26 with the edge of the sole itself. As the forward end portion of the shank of the sole is brought into the field of operations of the cutter one of the curved edge portions 76 of the templet engages the roller 26, causing the sole to be moved away from the cutter at such a point as to terminate the shank reducing cut at a predetermined point, preferably at the ball line. The templet then serves to hold the sole away from the cutter until the opposite lateral edge of the sole in the vicinity of the ball line has reached a position opposite the cutter. Thereafter the cut at this side of the sole is made in a manner similar to that above described in which the initial cut was made, except that the cut begins at the ball line and terminates at the heel breast line; the ends of the cut at the ball and heel breast lines being predetermined by the templet while the shape and width of the cut along the shank is gaged from the edge of the sole itself instead of from the edge of the templet.

Having thus described my invention, what I claim as new and desire to secure by Letters Patent of the United States is:

1. That improvement in methods of operating upon soles which consists in positioning a sole upon a sole supporting templet, separately securing both ends of the sole

against edgewise displacement upon the templet, operating upon the sole progressively lengthwise of the sole edge while utilizing the templet in gaging the relative movement between the sole and operating means in the plane of the sole at one portion of an area to be operated upon, and gaging said relative movement from the sole itself along another portion of the area to be operated upon.

2. That improvement in methods of thin edging soles which consists in positioning a sole upon a sole supporting templet, separately securing both ends of the sole against edgewise displacement upon the templet, cutting the sole progressively lengthwise of the sole edge while utilizing the templet in gaging the relative edgewise movement between the sole and the cutting means at one portion of the edge of the sole, and gaging said relative movement from the sole edge itself along another portion thereof.

3. That improvement in methods of beveling sole margins which consists in cutting a sole progressively lengthwise of the sole edge while utilizing a templet in gaging the relative movement between the sole and the cutter at the ends of the cut in the plane of the sole, and utilizing portions of the sole edge offset from the point of cutting in the direction of said relative movement in gaging said movement between the ends of the cut.

4. That improvement in methods of shank reducing soles by operating upon a sole progressively lengthwise of the sole edge which consists in positioning a sole upon a sole supporting templet, gaging the relative movement between the sole and a reducing instrumentality along opposite sides of the shank from the adjacent edges of the sole, and utilizing the templet in gaging said relative movement in the plane of the sole at opposite sides of the shank in the vicinity of the ball line.

45 5. That improvement in methods of shank reducing soles by operating upon a sole progressively lengthwise of the sole edge which consists in gaging the relative movement of the sole and the operating instrumentality by engagement with the edge of the sole between the ball line and the heel breast line, and utilizing a templet to support the sole near the ball line and the heel breast line and to gage said relative movement near said portions of the sole.

6. That improvement in methods of shank reducing soles which consists in moving a sole in its own plane relatively to a reducing instrumentality while utilizing the edge of a sole supporting templet to control said movement and thereby determine the location of one end of a shank reducing cut, and reducing the shank portion of the sole by cutting progressively lengthwise of the sole edge while determining the location of the reduc-

ing cut widthwise of the sole by gaging from the edge of the sole itself.

7. In a machine for operating upon the margins of shoe soles, in combination, an operating tool, a sole supporting templet, and a gage, the operating tool and the templet being adapted for relative movement to transfer the point of operation of the tool along the margin of the sole, and the templet having a portion wider than the sole to control an operation performed at one portion of the sole margin and another portion narrower than the sole to enable the sole itself to cooperate with the gage to control an operation upon another portion of the sole margin.

8. In a machine for operating upon the margins of shoe soles, in combination, an operating tool, a gage, and a sole supporting templet adapted to be moved relatively to the tool and shaped to cooperate with the gage to hold the tool away from a portion of the sole and to enable the edge of the sole to cooperate with the gage to enable another portion of the sole to be operated upon by said tool and to guide the sole during said operation.

9. In a machine for operating upon the margins of shoe soles, in combination, an operating tool, a sole supporting templet, and a gage, the templet being movable relatively to the tool and having part of its edge shaped to cooperate with said gage to control an operation performed at one portion of the margin of a sole on the templet and having another portion of its edge shaped to avoid engagement with the gage so that the latter may co-operate with the edge of the sole itself to control an operation performed upon another portion of the sole margin.

10. In a machine for shank reducing soles, in combination, a cutter, an edge gage, and a sole supporting templet, having end portions adapted to project beyond the edges of a sole supported thereby to hold the ends of the sole away from the cutter and an intermediate portion the edges of which are adapted to be within the outline of the shank portion of a supported sole to enable the sole edge to cooperate with the gage at the shank of the sole.

11. In a machine for shank reducing soles, in combination, a cutter, an edge gage, and a sole supporting templet, having end portions adapted to project beyond the edges of a sole supported thereby to hold the ends of the sole away from the cutter and an intermediate portion the edges of which are adapted to be within the outline of the shank portion of a supported sole to enable the sole edge to cooperate with the gage at the shank of the sole, the templet being also shaped to predetermine the locations of the ends of the shank reducing cuts.

12. In a shank reducing machine, the combination with a rotary cutter, of a sole supporting templet shaped to guide a sole into

and out of the field of operations of the cutter, a table inclined with respect to the axis of the cutter for supporting the templet, to enable the cutter to bevel the sole edge, means for adjusting the inclination of the table to vary the angle of bevel, and a gage on the table for co-operating with the templet in guiding the sole.

13. In a shank reducing machine, the combination with a rotary cutter, of a sole supporting templet to guide a sole relatively to the cutter, a table inclined with respect to the axis of the cutter for supporting the templet to enable the cutter to bevel the sole edge, means for adjusting the inclination of the table to vary the angle of bevel, and means for adjusting the table both vertically and horizontally to compensate for variations in the adjustment of the inclination of the table.

14. In a shank reducing machine, in combination, a cutter, a sole supporting templet, means on the templet adapted to engage the edge of a sole on the templet to hold the sole against edgewise displacement thereon, means for supporting the templet and sole at an inclination to the line of contact between the cutter and the sole, and means for co-operating with the templet to guide the sole as the templet is fed across the table.

15. In a shank reducing machine, in combination, a cutter, a sole supporting templet having means for preventing edgewise displacement of the sole relatively thereto, a table for supporting the templet, means on the table for engaging and guiding the templet as it is fed over the table, said templet having a portion shaped to cooperate with the engaging and guiding means, and another portion of the templet being shaped to permit the engaging and guiding means to cooperate with the edge of the sole, and means for holding the sole against the templet and the templet against the table.

16. In a shank reducing machine, in combination, a cutter, a sole supporting templet having means engaging the edge of the sole for preventing widthwise displacement of the sole relatively to the templet, means for supporting and guiding the templet as it is fed past the cutter, and a presser foot for engaging the sole in advance of the point of contact between the cutter and the sole for holding the sole against the templet while the sole is being operated upon.

17. In a shank reducing machine, in combination, a cutter, a sole supporting templet movable relatively to the cutter, means for preventing edgewise displacement of the sole relatively to the templet, means for supporting and guiding the templet as it is moved relatively to the cutter, a presser foot arranged to engage the sole at a point immediately in advance of the cutter, and a second presser foot for engaging the sole at a point

spaced inwardly from the point of operation of the cutter.

18. In a shank reducing machine, in combination, a cutter, a sole supporting templet, means on the templet for engaging the edge of the sole at opposite sides of the heel and toe portions thereof to prevent edgewise displacement of the sole relatively to the templet, means for supporting and guiding the templet as it is moved relatively to the cutter, and means for holding the sole against the templet in advance of the cutter.

19. In a shank reducing machine, in combination, a cutter, a sole supporting templet shaped to guide a sole into and out of engagement with the cutter, means engaging the edge of the sole on the templet for securing the sole against edgewise displacement of the sole in any direction relatively to the templet, and means for supporting and locating the templet with the edge of the sole in position to be beveled by the cutter and for guiding the templet as the sole is fed past the cutter to predetermine the location of the end of the cut.

20. In a shank reducing machine, in combination, a cutter, a templet adapted to be moved relatively to the cutter and to support a sole and provided with means for engaging the edge of the sole to prevent edgewise displacement of the sole in any direction relatively to the templet, the templet being shaped to cause the cutter to begin and end its action upon the sole at the forward and rear portions of the shank and to enable the width of the cut to be gaged from the edge of the sole between the ends of the shank portion of the sole.

21. In a shank reducing machine, in combination, a cutter, a templet adapted to be moved relatively to the cutter and to support a sole and hold it against edgewise displacement relatively to the templet, the templet having a portion of its edge spaced outwardly from the edge of the sole and shaped and arranged to predetermine the location of one end of a shank reducing cut and another portion of its edge spaced inwardly from the sole edge to enable the major portion of the cut to be gaged from the edge of the sole itself.

22. In a shank reducing machine, in combination, a cutter, a gage, and a templet adapted to be moved relatively to the cutter and the gage and to support a sole and hold it against edgewise displacement relatively to the templet, the templet having an edge portion shaped and arranged to cooperate with the gage to predetermine the location of one end of a shank reducing cut and having another edge portion shaped to enable the reducing cut along the shank to be gaged by cooperation of the gage with the edge of the sole itself.

23. In a shank reducing machine, the combination with a rotary cutter, of a templet

adapted to be fixed relatively to a sole to guide the sole relatively to the cutter, a table inclined with respect to the axis of the cutter for supporting the templet and sole to enable
5 the cutter to bevel the edge of the sole, means for supporting the table at different angles of inclination, and a gage on the table for co-operating with the templet.

24. For use in a shank reducing machine,
10 a sole supporting templet adapted to be secured in fixed relation to a sole and having marginal portions adapted to project beyond the edges of the ball and heel portions of the sole to determine the location of the ends
15 of reduced portions of the sole edge, said templet having other marginal portions adapted to be spaced inwardly from the shank portion of the sole to enable the locations of said reduced portions widthwise of the sole
20 to be gaged from the adjacent edges of the sole itself.

25. For use in a shank reducing machine, a sole supporting templet having means for holding a sole in fixed relation thereto, the
25 templet projecting beyond the toe and heel portions of the sole to hold corresponding portions of the sole away from an operating instrumentality of a shank reducing machine and having a shank portion which is narrower than the shank portion of the sole and is arranged relatively to the latter to permit a reducing operation along the shank of the sole to be gaged from the edge of the sole itself.

35 26. For use in a shank reducing machine, a sole supporting templet having means for securing the toe and heel portions of the sole against edgewise displacement and having its margin shaped to guide the sole to locate the
40 ends of the shank reducing cuts at the heel and breast lines respectively of the sole and to permit the shank reducing cuts to be gaged from the edge of the sole itself during operation along opposite sides of the shank.

45 In testimony whereof I have signed my name to this specification.

ERASTUS E. WINKLEY.
